CLAIM

The ornamental design for a clock, as shown and described in the drawings.

DESCRIPTION

FIG. 1 is a perspective view of the clock in accordance with the design of the invention showing the clock face in dotted lines;

FIG. 2 is a top view of the clock in accordance with the design of this invention;

FIG. 3 is a front view in elevation of the clock in accordance with the design of this invention with the clock face in dotted lines;

FIG. 4 is one side view of the clock design and which view is like the other side view of the clock design of this invention;

FIG. 5 is a bottom view of the clock design in accordance with the invention; and,

FIG. 6 is a rear view in elevation of the clock design of this invention.

The broken line showing of a dial in FIGS. 1 and 3 is for illustrative purposes only and forms no part of the claimed design.
